UNITED STATES PATENT OFFICE.

ALGOT LEVIN CHRISTENSON, OF STOCKHOLM, SWEDEN.

CENTRIFUGAL SEPARATOR.

SPECIFICATION forming part of Letters Patent No. 739,648, dated September 22, 1903.

Application filed September 23, 1902. Serial No. 124,529. (No model.)

To all whom it may concern:

Be it known that I, ALGOT LEVIN CHRISTENSON, a subject of the King of Sweden and Norway, and a resident of Sturegatan 13, Stockholm, Sweden, have invented a new and useful Improvement in Centrifugal Separators, of which the following is a specification, reference being had to the drawings accompanying and forming a part hereof.

This invention relates to improvements in centrifugal separators.

The object of the invention is to provide a liner which will be of the simplest possible construction and at the same time of great efficiency.

The invention consists, chiefly, in combining with a preferably conical mantle arranged in a usual separator-drum and having longitudinally-running folds of wings attached to and extending from the outer parts of said folds to or nearly to the wall of the separator-drum. The said wings may be plane, curved, corrugated, perforated, or formed in any other convenient manner, and they may be placed radially or not and vertically or inclined, as desired.

In the accompanying drawings I have shown a suitable constructional form of my invention.

Figure 1 shows a vertical section of a centrifugal separator-drum provided with a liner according to my present invention. Fig. 2 shows a top view of the drum and the liner, the cover of the drum and the plate securing the liner in position being partly broken away; and Fig. 3 shows the liner itself, seen from below.

The liner illustrated in the drawings consists of a preferably conical mantle 1, arranged centrally in a usual centrifugal drum 2 and provided in well-known manner with longitudinally-running folds, which at their outer parts are provided with holes or openings 3. To the said mantle are attached wings 4, extending from the outer parts of said folds to the wall of the drum 2. The said wings 4 may either be plane or they may be corrugated, as shown at 4^a, or folded in any convenient manner. Though I prefer to arrange the wings 4 in plane with one of the two sides of each fold, they may also be ar-

ranged in other manner, as shown at 4^b and 4^c in Fig. 2. The simplest manner in which the liner may be carried out is shown in Fig. 3. According to said figure the mantle and 55 the wings are made of a number of metal plates 4^d, each of which is bent at an angle forming an inward fold of the mantle. The said metal plates may be soldered together or fixed to each other in any other convenient 60 manner, so that they form a combination of a mantle and wings of the same kind as described above.

The drum 2 is in well-known manner provided with a central inlet-pipe 5, which, however, may be dispensed with, if desired. The said inlet-pipe is at its lower end provided with openings 8 for the full milk, let into the said pipe in usual manner. The drum 2 is further provided with one or more blue-milk outlets 6 and one or more cream-outlets 7. The latter may preferably be arranged at such radial distance from the geometric axis of the drum that the wall of cream during the separation will place itself in line 75 with the inner parts of the folds of the mantle at the top of the latter.

The liner may be held in position by means of a ring-shaped plate 9, the central opening of which may be of such size that the plate 80 rests only on the wings, as shown at 9^a in Fig. 2, or the inner edge of the plate may be cut out in accordance with the upper edge of the folded mantle, as shown at 9^b in Fig. 2. In this case the points of the plate thus obtained 85 may be cut away, so as to leave openings 9^c for the cream flowing upward on the outside of the mantle.

The liner described above works in the following manner. The full milk let in through 90 the pipe 5, if such be used, is thrown out through the openings 8 into the folds of the mantle, where it gradually rises accordingly as new milk is let in through the pipe 5. The blue milk gradually separating itself from 95 the cream will flow out through the openings of the mantle. The cream particles following the blue milk through the said openings will immediately move inward into the folds of the mantle and flow upward toward the 100 cream-outlet 7 of the drum. Since the said cream-outlet is arranged at such radial dis-

tance from the geometric axis of the drum that the wall of cream reaches somewhat into the folds of the mantle, the said folds may be made so deep as to leave sufficient space 5 outside the wall of cream for all the full milk gradually let in through the inlet-pipe 5 in order that the said full milk may not disturb the wall of cream nor mix itself with the latter. Obviously, also, the inward folds of 10 the mantle may be provided with openings, if desired, though I have not shown such in the drawings.

Having now particularly described my invention and in what manner the same may be 15 performed, what I claim as new, and desire to secure by Letters Patent, is—

1. In a centrifugal separator the combination with the bowl, of a longitudinally-folded partition, and wings attached to and extending 20 from the outer parts of the folds of said

partition, substantially as and for the purpose set forth.

2. The combination of, a centrifugal separator-bowl having cream and blue-milk outlets and an inlet-pipe for the full milk, and a 25 liner inside said bowl consisting of a longitudinally-folded partition, and wings attached to and extending from the outer parts of the folds of said partition, the latter being provided with outlet-openings at the outer parts 30 of the folds, substantially as and for the purpose set forth.

In testimony whereof I have signed my name to this specification in the presence of two subscribing witnesses.

ALGOT LEVIN CHRISTENSON.
